UNITED STATES PATENT OFFICE.

WALTER MARTIN TAYLOR, OF LONDON, ENGLAND.

GAS-FIRED WATER-HEATER OR STEAM-GENERATOR.

1,328,856.

Specification of Letters Patent.

Patented Jan. 27, 1920.

Application filed September 3, 1918. Serial No. 252,431.

To all whom it may concern:

Be it known that I, WALTER MARTIN TAYLOR, a subject of the King of Great Britain, residing in London, England, have invented 5 certain new and useful Improvements in Gas-Fired Water-Heaters or Steam-Generators, of which the following is a specification.

My invention relates to gas-fired water- 10 heaters or steam generators of the kind wherein a twin spiral water-coil unit is supported with two pipes constituting the unit lying in a horizontal plane immediately above and one on each side of the line of the 15 gas exit slot or holes of a gas burner consisting of a tube spirally coiled to occupy a horizontal plane, and wherein one or more single-pipe water-coil units are arranged individually in superposed position in closely 20 adjacent horizontal planes above the twin water-coil unit next to the burner, for instance as described in my prior United States Patent No. 916,936. It consists in improved construction and arrangement of 25 parts as hereinafter referred to, the principal objects being to reduce the cost of manufacture, to promote a better flow of water immediately above the gas burner, and a more equal distribution of gas in the burner, 30 and so to produce a more efficient water heater of the type referred to.

In known water-heaters of the above kind, the gas burner tube employed has the form of a single spiral of several turns or convolutions lying in one plane, gas being led into the several tubular convolutions by means of cross or radially disposed tubular arms communicating with a gas supply. In such heaters, the pipes constituting the two 40 spirals of the twin water-coil unit, immediately above the gas burner, have been reversely coiled and each spiral has comprised several turns or convolutions, the several convolutions of one spiral or coil being disposed so as to be each in contact or in juxtaposed relation with a convolution of the other coil, the contacting or juxtaposed convolutions following the line of holes or the slot provided in the crown of the gas burner 50 tube for the exit of the gas, a pipe convolution being on each side of the line. The twin coils of pipe are connected together by a suitable coupling so that water circulates through the respective coils and consequently 55 in the adjacent or twin coils above each convolution of the burner tube in reverse di-

rections. By adopting the improved construction of the present invention the following advantages accrue:

(1) A reversal of the flow in the water 60 coil unit immediately above the burner is obviated, the water circulating continuously in one direction throughout the unit;

(2) A greater proportion than heretofore of heating surface to the volume of water 65 passing through the said coil unit is provided; and

(3) The arrangement of a double or twin-coil disposed above the gas outlets in the burner tubing is attained without resource 70 to the use of two coils coupled together as above described.

I will describe the improvements constituting my present invention with reference to the accompanying drawings illustrating 75 the improved water heater or steam generator, and in which Figure 1 is a plan of the improved gas burner; Fig. 2 is a plan of the bottom water coil unit; Fig. 3 is a vertical section through the heating apparatus, 80 the section of the burner being taken along the line 3, 3 in Fig. 1; Fig. 4 is a fragmentary vertical section showing a modified form of the gas burner; Fig. 5 is a fragmentary section of peripheral portions of 85 the water-coil units showing a modification, and Fig. 6 is a section through a portion of a water-coil unit showing a further modification.

On referring to the drawing it will be 90 seen that the gas burner, which is preferably an integral casting as indicated in Fig. 4, but may be of built-up form as shown for instance in Fig. 3, consists of a number of spiral tubes *a*, each consisting of a single 95 convolution which is divided into a number of portions or sections by a number of radially disposed gas supply tubular arms *b* which extend from a central chamber *b'* to which is connected the gas supply conduit 100 *c*. The several spiral tubes *a* are each portions of different spirals; they constitute together what may be termed a broken spiral and communicate each with the gas supply arms *b*. The inlets to tube *a* being distributed along the arms *b* an equalized distribution of gas to the several tubes is obtained. These one-turn spiral tubes *a* are provided with nipples, slots or orifices *b* along the tops thereof and they are suitably 105 spaced apart, as shown in Fig. 1 to permit the passage of air between them. The water

- coil unit immediately over the burner consists of a single water pipe *d* which is spirally coiled and so arranged that it follows the line of the gas exits *b*², first on one side 5 of the line of exits of one tube and then on the other side thereof, so that it makes two convolutions above the first spiral gas tube, thus forming a twin water-coil spiral, before it advances toward the next adjacent or 10 second spiral gas tube, where it proceeds in the same manner along both sides of its gas exits before it passes on to the third and the succeeding spiral gas tubes, following the gas exits of each as just described.
- 15 In this way there is a portion of pipe *d* along each side of the lines of gas exits and the water is made to circulate continuously in one direction from one end of the pipe to the other without any reversal in the flow 20 and without any diminution in the area of pipe surface exposed to the gas flames, while the necessity of employing coil couplings, above referred to, is obviated.

A further improvement resides in the 25 shape that is preferably given to the pipe *d* constituting the water-coil unit immediately over the gas burner, for the purpose of preventing any water of condensation, that may happen to collect on the outer surface of the 30 pipe, from dropping on to the exits or orifices in the gas tubes and causing corrosion and clogging thereof. To this end I give the pipe a flattened circular or elongated elliptical section arranging the juxtaposed 35 portions of the piping so that the major axes of the so called elliptical sections are mutually inclined and form an inverted V above the orifices, so that any water of condensation dropping from the water-coil will tend 40 to fall clear of the orifices and of the burner tubes.

The flattened section form of the pipe has the additional advantage that in any length of pipe the proportion of the area of pipe 45 surface exposed to the gas flame to the quantity of water contained in the length of pipes is greater than in the case of a pipe having a circular section, so that a greater absorption of heat results.

50 A water-coil unit formed of a pipe *d* having a flattened section is shown in Fig. 3. Such a coil is preferably formed in the first instance of a pipe of circular section which after being spirally coiled is flattened in any 55 suitable manner, as for instance by means of a hydraulic press and dies.

When the water coil pipe *d* is of flattened section, then at each point where it passes from one convolution of the gas burner to 60 the next convolution thereof, the pipe may be given a suitable bend, as indicated at *d*, to make it assume the proper position alongside the gas exits of the latter burner coil.

The water piping in each of the layers of 65 coil superposed above the twin coils is ar-

ranged spirally and, preferably, in such a manner that the convolutions in any layer are substantially contiguous one with another, and so that the water circulates through the piping in a direction opposed to the flow 70 of the heated air and gases passing between the layers of coils, so that the water may be thereby gradually heated and raised to a desired temperature before being discharged at the outlet. The piping is continued from 75 one layer to the next, with or without suitable couplings. In Fig. 3 the coiled piping of two upper layers is shown at *e* and *f* respectively.

The lowermost water coil unit consisting 80 of the bank of twin coils is preferably shrouded along one or both of its peripheries. Such shrouding may be constituted by portions of water piping extending in dependent fashion from one or more of the 85 superposed upper layers of water-coil units, as indicated for example at *e'*, *f'* in Fig. 3. These shrouding portions of piping serve as baffles and tend to direct the course of the heated air and gases flowing through the apparatus. Alternatively, the shrouding may consist of a cylindrical plate, such as is shown at *g* in Fig. 5, the plate being supported from an upper coil layer by means of an inwardly projecting flange or lug 95 piece *g'*.

The convolutions of the piping in the layers *e* and *f* superposed above the lowermost water-coil unit may, alternatively, be suitably spaced apart and be spanned by a cover 100 plate or plates *h* as shown in Fig. 6. In this way the heated air and gases may be caused to flow over a greater extent of a pipe's surface.

A number of suitably shaped metallic 105 spacers or cradles such as the members *i* in Fig. 3, may be placed between the several water coil units *d*, *e*, *f* to keep them in proper position, and the nest of coil units may be supported on lugs or brackets projecting from the interior wall of an appropriate casing in which the heater would 110 be inclosed but which is not shown in the drawings.

Having thus described the nature of the 115 said invention and the best means I know of carrying the same into practical effect, I claim:—

1. A water heater comprising in combination a gas burner consisting of a series of 120 spiral tubes of successively increasing periphery and co-axially arranged in a horizontal plane to form a broken spiral, each tube being one convolution in length and provided along its crown with a line of 125 openings, a central chamber arranged co-axially with the spiral tubes, a gas supply conduit communicating with the interior of the chamber, a plurality of radially disposed tubular arms connecting the central cham- 130

ber and the spiral tubes, and a water coil consisting of a plurality of coiled pipe-units superposed one above the other, the lowermost pipe-unit being located above the gas 5 burner and consisting of a single pipe spirally coiled and arranged to make two circuits in succession above each of the said spiral tubes thereby causing the water to circulate twice over each spiral tube and 10 continuously in one direction from one end of the pipe to the other.

2. A water heater comprising in combination a gas burner consisting of a series of spiral tubes of successively increasing periphery and co-axially arranged in a horizontal plane to form a broken spiral, each tube being one convolution in length and provided along its crown with a line of 15 openings, a central chamber arranged co-axially with the spiral tubes, a gas supply conduit communicating with the interior of the chamber, a plurality of radially disposed tubular arms connecting the central chamber and the spiral tubes, a water coil consisting of a plurality of coiled pipe-units superposed one above the other, the lowermost pipe-unit being located above the gas 20 burner and consisting of a single pipe spirally coiled and arranged to make two circuits in succession above each of the said spiral tubes thereby causing the water to circulate twice over each spiral tube and continuously in one direction from one end of the pipe to the other, the said 25 pipe having a flattened circular section, the major axes of the sections of the two juxtaposed portions of the pipe above any one of the spiral tubes being inclined upwardly toward one another, for the purpose described.

3. A water heater comprising in combination a gas burner consisting of a series of spiral tubes of successively increasing periphery and co-axially arranged in a horizontal plane to form a broken spiral, each 30 tube being one convolution in length and provided along its crown with a line of openings, a central chamber arranged co-axially with the spiral tubes, a gas supply conduit communicating with the interior of the chamber, a plurality of radially disposed tubular arms connecting the central chamber and the spiral tubes, a water coil consisting of a plurality of coiled pipe-units superposed one above the other, the lowermost pipe-unit being located above the gas 35 burner and consisting of a single pipe spirally coiled and arranged to make two circuits in succession above each of the said spiral tubes thereby causing the water to circulate twice over each spiral tube and continuously in one direction from one end of the pipe to the other, and means adapted to direct the course of heated gases flowing from the burner through the heater, said 40 means consisting of shrouding members supported from the superposed pipe-units and located around the peripheral portions thereof.

4. A water heater comprising in combination a gas burner consisting of a series of spiral tubes of successively increasing periphery and co-axially arranged in a horizontal plane to form a broken spiral, each tube being one convolution in length and provided along its crown with a line of 45 openings, a central chamber arranged co-axially with the spiral tubes, a gas supply conduit communicating with the interior of the chamber, a plurality of radially disposed tubular arms connecting the central chamber and the spiral tubes, a water coil consisting of a plurality of coiled pipe-units superposed one above the other, the lowermost pipe-unit being located above the gas 50 burner and consisting of a single pipe spirally coiled and arranged to make two circuits in succession above each of the said spiral tubes thereby causing the water to circulate twice over each spiral tube and continuously in one direction from one end of the pipe to the other, and means adapted to direct the course of heated gases flowing from the burner through the heater, said 55 means consisting of shrouding members supported from the superposed pipe-units and located around the peripheral portions thereof.

5. A water heater comprising in combination a gas burner consisting of a series of spiral tubes of successively increasing periphery and co-axially arranged in a horizontal plane to form a broken spiral, each tube being one convolution in length, and provided along its crown with a line of 60 openings, a central chamber arranged co-axially with the spiral tubes, a gas supply conduit communicating with the interior of the chamber, a plurality of radially disposed tubular arms connecting the central chamber and the spiral tubes, and a water coil consisting of a plurality of coiled pipe-units superposed one above the other, the lowermost pipe-unit being located above the gas 65 burner and consisting of a single pipe spirally coiled and arranged to make two circuits in succession above each of the said spiral tubes thereby causing the water to circulate twice over each spiral tube and continuously in one direction from one end of the pipe to the other, and means adapted to direct the course of heated gases flowing from the burner through the heater, said 70 means consisting of shrouding members supported from the superposed pipe-units and located around the peripheral portions thereof.

6. A water heater comprising in combination a gas burner consisting of a series of spiral tubes of successively increasing periphery and co-axially arranged in a horizontal plane to form a broken spiral, each tube being one convolution in length, and provided along its crown with a line of 75 openings, a central chamber arranged co-axially with the spiral tubes, a gas supply conduit communicating with the interior of the chamber, a plurality of radially disposed tubular arms connecting the central chamber and the spiral tubes, and a water coil consisting of a plurality of coiled pipe-units superposed one above the other, the lowermost pipe-unit being located above the gas 80 burner and consisting of a single pipe spirally coiled and arranged to make two circuits in succession above each of the said spiral tubes thereby causing the water to circulate twice over each spiral tube and continuously in one direction from one end of the pipe to the other, and means adapted to direct the course of heated gases flowing from the burner through the heater, said 85 means consisting of shrouding members supported from the superposed pipe-units and located around the peripheral portions thereof.

7. A water heater comprising in combination a gas burner consisting of a series of spiral tubes of successively increasing periphery and co-axially arranged in a horizontal plane to form a broken spiral, each tube being one convolution in length, and provided along its crown with a line of 90 openings, a central chamber arranged co-axially with the spiral tubes, a gas supply conduit communicating with the interior of the chamber, a plurality of radially disposed tubular arms connecting the central chamber and the spiral tubes, and a water coil consisting of a plurality of coiled pipe-units superposed one above the other, the lowermost pipe-unit being located above the gas 95 burner and consisting of a single pipe spirally coiled and arranged to make two circuits in succession above each of the said spiral tubes thereby causing the water to circulate twice over each spiral tube and continuously in one direction from one end of the pipe to the other, and means adapted to direct the course of heated gases flowing from the burner through the heater, said 100 means consisting of shrouding members supported from the superposed pipe-units and located around the peripheral portions thereof.

8. A water heater comprising in combination a gas burner consisting of a series of spiral tubes of successively increasing periphery and co-axially arranged in a horizontal plane to form a broken spiral, each tube being one convolution in length, and provided along its crown with a line of 105 openings, a central chamber arranged co-axially with the spiral tubes, a gas supply conduit communicating with the interior of the chamber, a plurality of radially disposed tubular arms connecting the central chamber and the spiral tubes, and a water coil consisting of a plurality of coiled pipe-units superposed one above the other, the lowermost pipe-unit being located above the gas 110 burner and consisting of a single pipe spirally coiled and so arranged that it follows the line of openings along the crown of one spiral tube first on one side of the line of openings and then forthwith on the other side thereof before it proceeds to follow the next adjacent spiral tube.

In testimony whereof I have signed my name to this specification.

WALTER MARTIN TAYLOR.
